UNITED STATES PATENT OFFICE.

WILLIAM C. BAKER, OF NEW YORK, N. Y.

DESIGN FOR A HEATER-BASE.

SPECIFICATION forming part of Design No. 16,804, dated July 20, 1886.

Application filed May 7, 1886. Serial No. 201,491. Term of patent 7 years.

To all whom it may concern:

Be it known that I, WILLIAM C. BAKER, of the city and State of New York, have invented a Design for a Heater-Base, of which the following is a specification.

This design is represented in the accompanying engravings, the two parts thereof being separated for greater clearness.

Figure 1 is a perspective view of the bottom plate of the base, and Fig. 2 is a perspective view of the upper part that sets upon the bottom plate to compose the design of the heater-base.

The design of the bottom plate is clearly shown in Fig. 1, in which the portion *a* is circular, having a double-molded edge at *b*, and the projecting front *c* is a segment of an ellipse, with the upper surface dishing, as shown at *e*, and the edge is rounded, as at *i*. The legs have rounding projections *k*, through which vertical holes pass. The cylindrical portion *l* of the base is of the same diameter as the part *a* of the bottom plate. The front of this cylinder is notched, as at *m n*. The

top of the base is a ring having upon its upper surface circular projections *p q*, and between the circular projections *p q* there are openings at *r*.

I claim—

1. In a design for a heater-base, the design of the circular plate *a*, with the double-molded edge *b* and the elliptical projecting front *c*, that is dishing upon its upper surface and rounded on the edge, substantially as described and shown.

2. In a design for a heater-base, the upper part of the heater-base, consisting of the cylinder *l*, notched in the front, the top ring having circular projections *p q*, and the openings at *r* in the ring between such projections *p q*, substantially as described and shown.

Signed by me this 5th day of May, A. D. 1886.

W. C. BAKER.
